UNITED STATES PATENT OFFICE.

MARTIN L. SENDERLING, OF JERSEY CITY, NEW JERSEY.

DESIGN FOR A BOLSTER-PLATE FOR VEHICLES.

SPECIFICATION forming part of Design No. 30,324, dated March 7, 1899.

Application filed February 7, 1899. Serial No. 704,860. Term of patent 7 years.

To all whom it may concern:

Be it known that I, MARTIN L. SENDERLING, a citizen of the United States, and a resident of Jersey City, in the county of Hudson and 5 State of New Jersey, have invented and produced a new and original Design for a Bolster-Plate for Vehicles, of which the following is a specification, reference being had to the accompanying drawings, forming a part 10 thereof.

The leading features of my design consist in a bolster-plate for vehicles presenting a pair of lugs or ears projecting from the opposite sides of one face of the plate, a pair of 15 flanges projecting from the opposite sides of the other face of the plate, and a groove in the face of the plate extending between the lugs or ears.

In the accompanying drawings, Figure 1 is 20 a view of the plate in side elevation. Fig. 2 is a top plan view, and Fig. 3 is an end view.

The bolster-plate is denoted by A, the pair of lugs or ears projecting from the opposite sides of one face of the plate by B B', the flanges which project from the opposite sides of the other face of the plate by C C', and the groove in the face of the plate, extending between the lugs or ears, by D.

What I claim is—

The design for a bolster-plate for vehicles 30 substantially as shown and described.

In testimony that I claim the foregoing as my invention I have signed my name, in presence of two witnesses, this 3d day of February, 1899.

MARTIN L. SENDERLING.
